Ultra Slim Wax Pen. By Skunk Labs. Dated Mar. 18, 2019. Found online [Nov. 30, 2020]. <https://www.skunklabshop.com/products/skunk-wax-pen> (Year: 2019).*Primary Examiner — Marissa J Cash*Assistant Examiner* — William B Melliar(74) *Attorney, Agent, or Firm* — Tommy S F Wang; Wang IP Law Group, P.C.(57) **CLAIM**

The ornamental design for a lighter, as shown and described.

DESCRIPTION

FIG. 1 is a perspective view of a lighter showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof with a stand being pulled out.

The broken line portions of the lighter in FIGS. 1-8 represent unclaimed portions of the claimed design and form no part thereof.

1 Claim, 5 Drawing Sheets(56)
